UNITED STATES PATENT OFFICE.

ROBERTO RODRIGUEZ, OF DETROIT, MICHIGAN.

COLD-AIR-SUPPLYING APPARATUS.

Application filed October 8, 1924. Serial No. 742,289.

This invention relates generally to a cooling apparatus intended for use in supplying cool air to halls, rooms, restaurants, shops or the like, the invention having for an object the provision of a novel and simple apparatus of this type, a further specific object relating to the provision of automatically adjustable heat insulating plates that control the entrance and exit ends of the cooling box.

For further comprehension of the invention, and of the objects and advantages thereof, reference will be had to the following description and accompanying drawing, and to the appended claims in which the various novel features of the invention are more particularly set forth.

Fig. 1 of the drawing is a side view of my improved cooling apparatus.

Fig. 2 is a transverse sectional view thereof, taken on the line 2—2 of Fig. 1.

Fig. 3 is a fragmentary longitudinal sectional view, this view being taken on the line 3—3 of Fig. 2.

Fig. 4 is a face view of the control switch, indicating also the electrical connection.

As here embodied my improved cooling apparatus comprises a box 10 which is provided at opposite ends with the heads 11 each formed with a series of apertures. Connected at opposite ends to these heads, and registering with the apertures therein, are tubes 12 which extend through the box from end to end thereof and through which the air to be cooled passes. The box 10 is adapted to be filled with ice, being here shown as formed in the top with a pair of doors 14 through which the ice may be inserted into the box, and with a drain cock 15, at the bottom. At its entrance end the box is covered with a fine mesh wire screen 16. Connected to the exit end of the box is a tapering member 17 that has a pipe or conduit 18 connected thereto, this pipe leading to the casing of an air blower indicated generally at 19 and having therein an ordinary helical fan 20 that may be driven by suitable means such as the electric motor 21.

In order to retard the melting of the ice in the box, when the apparatus is not in use, I provide at each end of the box a plate 24 of almost equal area to the cross sectional area of the box, these plates being located adjacent the heads 11 and being formed with a number of apertures 25, therein that

may be moved into and out of registry with the ends of the pipes 12 by vertical movement of the plates. These plates are preferably constructed to be heat insulating as will be understood. Connected to the top of each plate is a cord 26, these cords leading upward through apertures in the top of the box and around suitable pulleys 27 and being attached at their other ends to the respective pulleys 28 fixed on a common shaft 29 that is mounted in a bearing bracket 30 on top of the box 10. Connected to one of the pulleys 28, eccentrically thereof is a rod 35 that is connected also to the end of the plunger 36 of a solenoid 37 mounted on top of the box 10, so that upon energizing of the solenoid the cords 26 are pulled to raise the plates 24 and move their apertures into registry with the pipes 12. Fixed to the shaft 29 between the pulleys 28 is a disk 40 having in its periphery a notch 41 that is adapted to be engaged by a pawl 42 to retain the pulleys 28 in position with the plates raised, this pawl being pressed against the disk by a spring 43. The pawl 42 is provided with a tail-piece 42' on which is fixed the armature 44 of an electromagnet 45 which, when energized, lifts the pawl and allows the plates 24 to drop to position closing the openings into the pipes 12. These parts on the top of the box 10 may be covered by a housing 46.

A control switch is provided and is arranged to automatically lift the plates 24 to open the ends of the pipes 12 when the motor 21 is started, and to lift the pawl 42 to allow the plates to drop when the motor is stopped. This switch comprises a base 50 on which are mounted two pairs of spring contacts. Each pair comprises a short contact member 51 and a longer contact member 52 to the outer end of which is hinged a finger 53 that has a tail-piece 53' projecting along the said member to prevent swinging movement in one direction, movement in the other direction being yieldingly resisted by the spring 54. Upon the base is pivoted as at 55 switch arm 56 that carries a pin or stud 57 that is adapted to bear on the fingers 53 and so close one pair of contacts each time the arm 56 is swung between open and closed positions. The contacts that are closed when the switch arm swings to circuit closing position are wired to the solenoid 37, while the other pair of contacts, which are closed mo-

mentarily when the switch arm swings to open position, are wired to the electro-magnet 45.

In the operation of the device, the blower 5 and ice box may be positioned where desirable, and when the switch arm is thrown to close the circuit to the motor 21 the solenoid is momentarily energized and the pulleys 28 rotated to lift the plates 24, the pawl dropping into the notch 41. When the switch arm is moved in the opposite direction the circuit to the electro-magnet 45 is closed and the pawl is lifted, the plates 24 then dropping by gravity to position closing the ends 10 of the pipes 12.

Having thus described my invention what I claim as new and desire to protect by Letters Patent of the United States is as follows:—

20 In a cold air supplying apparatus, having an ice box housing air tubes provided with sliding shutter arrangements, the combination of a cord connected to the top of each of

said sliding shutters, pulleys mounted on the top of said ice box, said cords being guided 25 over said pulleys, a bearing bracket mounted on the top of said ice box, a shaft rotatable in said bearing bracket, pulleys fixed on said shaft, said cords being attached to said last mentioned pulleys, a disc also mounted 30 on said shaft, the periphery of said disc being formed with a notch, another bracket mounted on the top of said ice box, a pawl pivotally mounted on said last mentioned bracket, the front of said pawl being engageable with said notch to retain the last mentioned pulleys in position with the shutter arrangement open, an armature fixed to the rear of said pawl, and an electromagnet on 35 said last mentioned bracket, said electromagnet when energized being capable of moving said pawl to release the pawl from the said notch.

In testimony whereof I have affixed my signature.

ROBERTO RODRIGUEZ.
